ILLUMINATION CONTROL SYSTEM

Richard B. Hunter, Shorewood, Wis., assignor to
 Cutler-Hammer, Inc., Milwaukee, Wis., a corporation of Delaware

Application July 27, 1939, Serial No. 286,848

11 Claims. (Cl. 175—312)

This invention relates to improvements in illumination control systems.

The invention relates more particularly to illumination control systems comprising a plurality of lamp circuits with provision for presetting a plurality of intensities of illumination of each circuit and effecting transition from one preset intensity to another at selective rates, the different lamp circuits being selectively grouped together whereby the rates of transition of the various groups may differ from each other.

In a copending application, Serial No. 280,448, filed June 22, 1939, I have disclosed a system of the aforementioned character in which each of a plurality of lamp circuit controllers are selectively grouped and the respective groups connected to common master controllers, one for each group and each scene to be preset, so as to provide for transition from one scene to another at different selected rates for each group. In accordance with the present invention each lamp circuit controller is also provided with a plurality of scene controllers, and may be connected to the latter selectively through one of a plurality of faders which provide for transition from one scene to another at a selected rate determined by the speed of operation of the respective fader, the faders of such circuits for which the same rate of transition is desired being operated in unison.

An object of the present invention is to provide a system of the aforementioned character which may employ any type of voltage regulator in the lamp circuit for the control of the illumination intensity of the latter.

Another object is to provide a system in which potentiometers are employed for the pilot or sender control devices, which potentiometers may be of either the resistor or reactor type.

Another object is to provide a system including individual circuit and master controls wherein transition of the intensity of illumination of an individual circuit from one preset value to another is effected individually by means of a cross fader which transfers the individual lamp circuit from one preset control to another.

Another object is to provide a system of the aforementioned character wherein a plurality of individual fader controllers for the transfer of a circuit from one preset to another may be employed and in which the different individual cross faders may be operated at individual speeds.

Another object is to provide for the mechanical coupling of corresponding cross faders of a plurality of groups so that they are operated simultaneously.

Another object is to provide an illumination control of the aforementioned character wherein the transition from a given preset to another preset of the individual lamp circuit may be accomplished selectively either instantaneously or gradually through the use of a cross fader.

Another object is to provide a system in which any individual lamp circuit controller may selectively be controlled directly from its associated sender controller.

Other objects and advantages will hereinafter appear.

An illumination control system embodying the invention usually comprises a number of individual lamp circuits, each controllable selectively by a plurality of presettable pilot control devices, which may be operated either directly to control the brilliancy of the respective lamp circuit or which may be grouped under the control of one or a plurality of presettable master control devices to provide for joint control of the respective groups at proportionally varying intensities. In the system embodying the present invention a plurality of "fader" controllers are selectively interposed between the individual pilot control devices and the voltage responsive element of the lamp circuit controller to provide for transfer of the individual lamp circuit control from one preset intensity to another at selective rates.

The accompanying drawing is a diagram of a system incorporating the present invention. The system comprises two lamp circuits 1 and 2, respectively. Energy for the lamps and for the control circuits is supplied from the alternating current bus bars L¹ and L². The current for the lamp circuit 1 is supplied through an autotransformer dimmer 3 which has its winding connected across the lines L¹, L² and which is provided with a sliding contact 4 by means of which a variable secondary voltage of the transformer may be impressed upon the lamp circuit. The brush 4 connects the various taps of the transformer winding to a contact bar 5 to which one terminal of the lamp circuit is connected, while the other terminal of the lamp circuit is connected to the line L². The brush 4 may be moved along the transformer taps and bar 5 by a screw 6 which is driven by a motor 7 provided with reversing windings, the latter being controlled by a relay 8.

The relay 8 comprises a lever 8^a pivoted at its center and provided at each end with a magnet core 8^b. The relay is normally biased to a center position in any suitable manner. The cores are

surrounded by polarizing coils 8c which are connected across the lines L¹, L² in such a manner that the polarity of both cores is in the same direction. A second set of coils 8d is arranged on the cores 8b but these are wound in opposite directions relative to each other so that a current flowing therein unbalances the pull on the two cores to cause rotation of the armature in one or the other direction, depending upon the direction of the current in the coils 8d relative to that in the coils 8c. The lever 8a is provided with a contact arm 8e which when the lever is rotated makes contact with stationary contacts 8f and 8g, respectively, to thereby energize one or the other of the reversing windings of the motor 7 and cause the latter to rotate in a corresponding direction to thereby move the brush 4 and increase or decrease the lamp circuit voltage.

The circuit arrangement thus far described is duplicated for the lamp circuit 2 and any additional lamp circuits of the system.

The system further includes two scene master potentiometers 9 and 10, respectively, both being connected across the lines L¹, L² and being provided with sliding contacts 9a and 10a, respectively. Lamp circuit 1 is provided with two lamp group potentiometers 11 and 12, respectively, one for each scene, the potentiometers being connected between the line L¹ and the brushes 9a and 10a, respectively. Similar lamp group potentiometers 13 and 14, respectively, are provided for lamp circuit 2. Lamp circuit 1 is further provided with a double pole three position switch 15, having contact levers 15a and 15b, respectively, which are mechanically connected to move in unison and to make contact selectively with stationary contacts 15c and 15d, 15e and 15f and 15g, respectively. The contact lever 15a is connected to the movable contact 11a of potentiometer 11, while contact lever 15b is similarly connected to movable contact 12a.

A potentiometer or fader 16 is connected between the contacts 15c and 15d and a similar potentiometer or fader 17 between the contacts 15e and 15f. Faders 16 and 17 are provided with movable brushes 16a and 17a, respectively, forming a bridging contact between contact bars 16b and 17b, respectively, and the potentiometer impedances 16 and 17, respectively. The contact bars 16b and 17b are connected together and to the contact 15g.

A potentiometer rheostat 18 is connected between the lines L¹ and L² and is provided with a sliding contact 18a, which bridges a circuit between a variable point of the rheostat 18 and a bar 18b. The contact 18 is driven synchronously with the contact 4. The coils 8d are connected between the contact 15g and the bar 18b, so that a variable voltage impressed by the potentiometer 18 upon the coils 8d is a measure of the lamp circuit voltage and brilliancy.

The system operates as follows: let it be assumed that the switch 15 of lamp group 1 is positioned to energize fader 16 of that group and brushes 16a and 17a of all the faders of all the lamp groups are in their extreme left position. Also the switch 15 of lamp group 2 is closed to energize the corresponding fader 17. It is obvious therefore that the potentiometer 18 of group 1 must occupy a position to produce a voltage which is equal to the line voltage multiplied by the ratio of input to output voltage of master potentiometer 9 and further multiplied by the ratio of output to input voltage of lamp group 75 potentiometer 11. Similarly the output voltage of

the receiver potentiometer 18 of lamp group 2 is or will become equal to the line voltage as modified by the potentiometers 9 and 13. If it is now desired to change from scene 1 to scene 2 setup it is only necessary to adjust the potentiometers 10, 12 and 14 and thereafter move the respective fader brushes 16a and 17a from their extreme left to their extreme right position. This subjects the receiver potentiometers 18 to the control of scene master potentiometer 10 and lamp group 10 potentiometers 12 and 14, respectively. As a result the relays 8 are energized until the brilliancy of the lamps and the position of the receiver potentiometers again corresponds to the desired value as determined by the adjustment. 15

All of the brushes 16a and 17a, respectively, are coupled together mechanically, so that they may be moved simultaneously when changing from one scene to another. Furthermore by moving the brushes 16a at a rate which differs from that of the brushes 17a, two different rates of fading from one scene to another may be provided for the different lamp groups. It is further possible to change the control of any lamp group instantly from control by group potentiometer 12 25 to control by group potentiometer 11 by moving the respective switch 15 into engagement with the contact 15g.

It will be observed that any type of preset master scene regulator may be employed which 30 is capable of supplying a plurality of preset voltages to the individual group potentiometers.

It will further be observed that the individual group masters may also be of either the resistor or the autotransformer type. 35

By moving the brushes 16a and 17a, respectively, of the various lamp group controllers to an intermediate position it is further possible to subject the relays 8 and therefore the various lamp groups to a combined influence of the controllers 40 for scene 1 and scene 2. These two impress upon the regulator a voltage which is the resultant of the voltages obtaining on the lamp scene regulators 11 and 12, respectively.

The respective fader brushes 16a and 17a are 45 provided with suitable means whereby they are coupled to a joint operating handle 19 or the like for simultaneous operation of the faders so coupled at a given rate. Obviously all the faders of the system may be arranged in several groups 50 for operation at different rates for the several groups.

What I claim as new and desire to secure by Letters Patent is:

1. A control system comprising a circuit to be 55 controlled, voltage responsive means for controlling said circuit, and means for presetting a plurality of operating values for an electrical condition of said circuit comprising a voltage regulator for each of said values and a plurality of 60 selectively connectable faders for each pair of said voltage regulators and adapted to increase the effect of one of said regulators and simultaneously decrease the effect of the other of said regulators upon said voltage responsive means. 65

2. A control system comprising a circuit to be controlled, an electromagnetic relay for controlling said circuit, a plurality of voltage regulators each adapted to supply a variable voltage to said relay to operate same and a plurality of selectively connectable faders for each pair of said voltage regulators and adapted to increase the effect of one of said regulators and simultaneously decrease the effect of the other of said regulators upon said relay. 70 75

3. A control system comprising a circuit to be controlled, an electromagnetic relay for controlling said circuit and having an energizing winding, a plurality of potentiometers each adapted to supply a variable output voltage, and a plurality of faders for said plurality of potentiometers each connectable selectively between the output terminals of a pair of said potentiometers and adapted to increase the effect of the output voltage of one and to simultaneously decrease the effect of the output voltage of the other of said pair of potentiometers upon said winding.
4. A control system comprising a circuit to be controlled, an electromagnetic relay for controlling said circuit, said relay having two energizing windings, a voltage regulator adapted to impress a voltage on one of said windings which varies with an operating value of said circuit, a plurality of potentiometers each adapted to supply a variable output voltage corresponding to a selected operating value of said circuit, and a plurality of faders each connectable selectively between the output terminals of a pair of said potentiometers and adapted to increase the effect of the output voltage of one and to simultaneously decrease the effect of the output voltage of the other of said pair of potentiometers upon said other of said windings.
5. A control system comprising a circuit to be controlled, an electromagnetic relay for controlling said circuit, said relay having two energizing windings, a voltage regulator adapted to impress a voltage on one of said windings which varies with an operating value of said circuit, a plurality of potentiometers each adapted to supply a variable output voltage corresponding to a selected operating value of said circuit, and a plurality of faders each connectable selectively between the output terminals of a pair of said potentiometers and adapted to increase the effect of the output voltage of one and to simultaneously decrease the effect of the output voltage of the other of said pair of potentiometers upon said other of said windings, and means to impress the output voltage of a given one of said potentiometers upon said second winding independent of the operation of said faders.
6. In an illumination control system affording individual and joint control of the intensity of a plurality of groups of lamps for the enactment of a plurality of scenes of illumination, comprising for each group of lamps, voltage responsive means for controlling said intensity, a plurality of selectively operable voltage regulators one for each of said scenes and affording a variable ratio between their respective input and output voltages, and a plurality of faders each selectively connectable to a pair of said voltage regulators and adapted to increase the effect of the output voltage of one and to simultaneously decrease the effect of the output voltage of another of said voltage regulators upon said voltage responsive means, and common means to vary simultaneously the input voltages of the respective scene regulators.
7. In an illumination control system affording individual and joint control of the intensity of a plurality of groups of lamps for the enactment of a plurality of scenes of illumination, comprising for each group of lamps, voltage responsive means for controlling said intensity, a plurality of selectively operable voltage regulators one for each of said scenes and affording a variable ratio between their respective input and output voltages, a plurality of faders each selectively connectable to a pair of said voltage regulators and adapted to increase the effect of the output voltage of one and to simultaneously decrease the effect of the output voltage of another of said voltage regulators upon said voltage responsive means, and means to impress the output voltage of a given one of said voltage regulators upon said voltage responsive means independent of the operation of said faders, and means for grouping said faders and operating the faders of the respective group jointly.
8. In an illumination control system affording individual and joint control of the intensity of a plurality of groups of lamps for the enactment of a plurality of scenes of illumination, comprising for each group of lamps, voltage responsive means for controlling said intensity, a plurality of presettable voltage regulators, one for each of said scenes and affording a variable ratio between their respective input and output voltages, a plurality of faders each selectively connectable to a pair of said voltage regulators and adapted to increase the effect of the output voltage of one and to simultaneously decrease the effect of the output voltage of another of said voltage regulators upon said voltage responsive means, and means for grouping said faders and operating the faders of the respective group jointly.
9. In an illumination control system affording individual and joint control of the intensity of a plurality of groups of lamps for the enactment of a plurality of scenes of illumination, comprising for each group of lamps, voltage responsive means for controlling said intensity, a plurality of presettable voltage regulators, one for each of said scenes and affording a variable ratio between their respective input and output voltages, a plurality of faders each selectively connectable to a pair of said voltage regulators and adapted to increase the effect of the output voltage of one and to simultaneously decrease the effect of the output voltage of another of said voltage regulators upon said voltage responsive means, and means to impress the output voltage of a given one of said voltage regulators upon said voltage responsive means independent of the operation of said faders, and means for grouping said faders and operating the faders of the respective group jointly.
10. In an illumination control system affording individual and joint control of the intensity of a plurality of groups of lamps for the enactment of a plurality of scenes of illumination, comprising for each group of lamps, voltage responsive means for controlling said intensity, a plurality of presettable voltage regulators, one for each of said scenes and affording a variable ratio between their respective input and output voltages, a plurality of faders each selectively connectable to a pair of said voltage regulators and adapted to increase the effect of the output voltage of one and to simultaneously decrease the effect of the output voltage of another of said voltage regulators upon said voltage responsive means, and means for grouping said faders and operating the faders of the respective group jointly, and common means to vary simultaneously the output voltages of the respective scene regulators.
11. In an illumination control system affording individual and joint control of the intensity of a plurality of groups of lamps for the enactment of a plurality of scenes of illumination, comprising for each group of lamps, voltage responsive means for controlling said intensity, means for

presetting a plurality of selectively operable voltage regulators, one for each of said scenes and affording a variable ratio between their respective input and output voltages, a plurality of faders 5 each selectively connectable to a pair of said voltage regulators and adapted to increase the effect of the output voltage of one and to simultaneously decrease the effect of the output voltage of another of said voltage regulators upon said volt-

age responsive means, means for grouping said faders and operating the faders of the respective group jointly, and means to impress the output voltage of a given one of said voltage regulators upon said voltage responsive means independent 5 of the operation of said faders, and common means to vary simultaneously the output voltages of the respective scene regulators.

RICHARD B. HUNTER.
